UNITED STATES PATENT OFFICE

RICHARD WILHELM von HOHENHOFF, OF BALTIMORE, MARYLAND

FOUNTAIN SHAVING BRUSH

Application filed February 17, 1932, Serial No. 593,604, and in Germany February 24, 1931.

This invention relates to certain new and useful improvements in fountain shaving brushes.

The primary object of the invention is to provide a fountain shaving brush wherein a brush head is removably mounted in one end of a tubular handle that is internally threaded with a piston threaded into the tubular handle for forcing shaving cream or the like through an opening in the brush head onto the brush bristles with the piston operated by an extensible piston rod formed of telescoping sections and an operating head swiveled on the other end of the tubular handle and fixedly engaged with the adjacent end of the extensible piston rod.

A further and important object of this invention resides in the provision of a fountain shaving brush of the foregoing character wherein the extensible piston rod for operating the piston is formed of telescoping sections rectangular in end elevation to insure a positive connection between the operating head and piston, as contrasted with prior devices wherein the extensible piston rod for operating the piston is formed of cylindrical telescoping sections relying upon friction between the parts for the feeding of the piston.

With the above and other objects in view that will become apparent as the nature of the invention is better understood, the same consists in the novel form, combination and arrangement of parts hereinafter more fully described, shown in the accompanying drawings and claimed.

In the drawing:

Figure 1 is a side elevational view of a fountain shaving brush constructed in accordance with the present invention;

Figure 2 is an inner end elevational view;

Figure 3 is a vertical longitudinal sectional view taken on line 3—3 of Figure 2, showing the removable brush head, the internally threaded tubular handle, the extensible piston rod for operating the piston and the operating head for the piston rod with the piston rod in its fully extended position;

Figure 4 is a sectional view, similar to Figure 3, showing the extensible piston rod in its fully retracted position;

Figure 5 is a cross-sectional view taken on line 5—5 of Figure 3; and

Figure 6 is a cross-sectional view taken on line 6—6 of Figure 3, showing the rectangular telescoping sections of the piston rod. 55

Referring more in detail to the accompanying drawing, there is illustrated a fountain shaving brush that may be constructed of any desired material and including a tubular handle 10 closed at its inner end by an end wall 11 while the outer end thereof is open, the tubular handle being internally threaded as at 12 over substantially the entire length thereof.

The brush head comprises a bristle portion 13 carried by a cylindrical head having a bottom wall 14 and an annular side wall 15 confining the brush bristles 13 and externally threaded for reception in the internally threaded open end of the tubular handle 10, the wall 15 carrying an edge bead 15a to limit inward movement of the brush head into the open end of the tubular handle. A central opening is formed in the bottom wall 14 of the brush head and is surrounded by a tubular boss 16 extending into the central portion of the body of the bristles 13 for the delivery of shaving cream or the like from the tubular handle onto the brush bristles. 65 70 75

To accomplish the feeding of the shaving cream from the tubular handle onto the brush bristles, there is provided a piston 17 threaded into tubular handle 10, the shaving cream being introduced into the tubular handle when the brush head is removed therefrom and the piston 17 is shifted in the tubular handle to a position adjacent the inner end thereof as illustrated in Figure 4. The operating means for the piston 17 includes an extensible piston rod formed of telescoping sections, one end section of the piston rod being connected to the piston and the other end section thereof being connected to an operating head swiveled upon the inner end of the tubular handle. The extensible piston rod is formed of a series of telescoping sections 18, rectangular in end elevation, each section comprising side walls flanged inwardly at their lower ends as at 19 and flanged outwardly at their upper ends as at 20, the 80 85 90 95

- flanges 19 and 20 cooperating to limit extensible or expansive movement of the sections 18. The opposite walls of each section 18 are parallel and the rectangular formation of the sections is relied upon to form a positive operative connection between adjacent sections as contrasted with telescoping sections that are cylindrical and taper and rely upon friction for a driving connection between adjacent sections. The connection between the outer piston rod section 18 and the piston 17 includes a plug 21 having a screw connection 22 at one end with the piston 17 while its other end telescopes into said end section 18 of the piston rod and is flanged outwardly as at 23 for engagement with the outer flange 19 upon said piston rod section, the plug 21 being rectangular in cross section as illustrated in Figure 5.
- 20 The inner end section of the extensible piston rod is provided with an inner end wall 24 and said wall 24 has the inner end of a screw 25 fixed thereto as at 26, the screw freely extending through a central opening 27 provided in the inner end wall 11 of the tubular handle 10 and carried by an operating disk head 28 rotatably mounted upon the inner end of the tubular handle.
- 30 By rotating the operating head 28 in a counterclockwise direction, the piston 17 that is illustrated in its fully extended position in Figure 3 is threaded through the tubular handle to occupy a position adjacent the inner end wall 11 and during this movement, the sections 18 of the extensible piston rod telescope within each other as shown in Figure 4 and provide a relatively large chamber within the tubular handle between the piston 17 and brush head for the introduction of shaving cream or the like upon removal of the brush head from the open end of the tubular handle. Upon rotation of the operating head 28 in a clockwise direction, the piston 17 is threaded through the tubular handle toward the open end thereof for the discharge of the shaving cream onto the brush bristles 13, the extensible piston rod rotating with the operating head 28 and piston 17 with the rectangular form of piston rod sections providing positive drive connections between adjacent sections and eliminating any tendency toward binding of the parts and assuring perfect operation of the device.
- 50 While there is herein shown and described the preferred embodiment of the invention, it is nevertheless to be understood that minor changes may be made therein without departing from the spirit and scope of the invention as claimed.
- 60 I claim:—
1. In a fountain shaving brush, a tubular internally threaded handle having an open end, a brush head removably mounted in the open end, a piston threaded in the handle, a piston rod for operating the piston formed of

telescoping sections rectangular in end view and interlockingly connected together and an operating head for the piston rod mounted on the inner end of the handle.

2. In a fountain shaving brush, a tubular internally threaded handle having an open end, a brush head removably mounted in the open end, a piston threaded in the handle, a piston rod for operating the piston formed of telescoping sections rectangular in end view and interlockingly connected together, an operating head for the piston rod mounted on the inner end of the handle, and a plug connection between the piston and piston rod anchored to the piston and telescoping into the adjacent piston rod section and being non-rotatable relative to said piston rod section.

70 3. In a fountain shaving brush, a tubular internally threaded handle having an open end, a brush head removably mounted in the open end, a piston threaded in the handle, a piston rod for operating the piston formed of telescoping sections rectangular in end view and interlockingly connected together, an operating head for the piston rod mounted on the inner end of the handle, and a plug connection between the piston and piston rod anchored to the piston and telescoping into the adjacent piston rod section and being non-rotatable relative to said piston rod section.

75 4. In a fountain shaving brush, a tubular internally threaded handle having an open end, a brush head removably mounted in the open end, a piston threaded in the handle, a piston rod for operating the piston formed of telescoping sections rectangular in end view and interlockingly connected together, an operating head for the piston rod mounted on the inner end of the handle, and a plug connection between the piston and piston rod anchored to the piston and telescoping into the adjacent piston rod section and being non-rotatable relative to said piston rod section.

80 5. In a fountain shaving brush, a tubular internally threaded handle having an open end, a brush head removably mounted in the open end, a piston threaded in the handle, a piston rod for operating the piston formed of telescoping sections rectangular in end view and interlockingly connected together, an operating head for the piston rod mounted on the inner end of the handle, and a plug connection between the piston and piston rod anchored to the piston and telescoping into the adjacent piston rod section and being non-rotatable relative to said piston rod section.

85 6. In a fountain shaving brush, a tubular internally threaded handle having an open end, a brush head removably mounted in the open end, a piston threaded in the handle, a piston rod for operating the piston formed of telescoping sections rectangular in end view and interlockingly connected together, an operating head for the piston rod mounted on the inner end of the handle, and a plug connection between the piston and piston rod anchored to the piston and telescoping into the adjacent piston rod section and being non-rotatable relative to said piston rod section.

90 7. In a fountain shaving brush, a tubular internally threaded handle having an open end, a brush head removably mounted in the open end, a piston threaded in the handle, a piston rod for operating the piston formed of telescoping sections rectangular in end view and interlockingly connected together, an operating head for the piston rod mounted on the inner end of the handle, and a plug connection between the piston and piston rod anchored to the piston and telescoping into the adjacent piston rod section and being non-rotatable relative to said piston rod section.

95 8. In a fountain shaving brush, a tubular internally threaded handle having an open end, a brush head removably mounted in the open end, a piston threaded in the handle, a piston rod for operating the piston formed of telescoping sections rectangular in end view and interlockingly connected together, an operating head for the piston rod mounted on the inner end of the handle, and a plug connection between the piston and piston rod anchored to the piston and telescoping into the adjacent piston rod section and being non-rotatable relative to said piston rod section.

100 9. In a fountain shaving brush, a tubular internally threaded handle having an open end, a brush head removably mounted in the open end, a piston threaded in the handle, a piston rod for operating the piston formed of telescoping sections rectangular in end view and interlockingly connected together, an operating head for the piston rod mounted on the inner end of the handle, and a plug connection between the piston and piston rod anchored to the piston and telescoping into the adjacent piston rod section and being non-rotatable relative to said piston rod section.

105 10. In a fountain shaving brush, a tubular internally threaded handle having an open end, a brush head removably mounted in the open end, a piston threaded in the handle, a piston rod for operating the piston formed of telescoping sections rectangular in end view and interlockingly connected together, an operating head for the piston rod mounted on the inner end of the handle, and a plug connection between the piston and piston rod anchored to the piston and telescoping into the adjacent piston rod section and being non-rotatable relative to said piston rod section.

110 11. In a fountain shaving brush, a tubular internally threaded handle having an open end, a brush head removably mounted in the open end, a piston threaded in the handle, a piston rod for operating the piston formed of telescoping sections rectangular in end view and interlockingly connected together, an operating head for the piston rod mounted on the inner end of the handle, and a plug connection between the piston and piston rod anchored to the piston and telescoping into the adjacent piston rod section and being non-rotatable relative to said piston rod section.

115 12. In a fountain shaving brush, a tubular internally threaded handle having an open end, a brush head removably mounted in the open end, a piston threaded in the handle, a piston rod for operating the piston formed of telescoping sections rectangular in end view and interlockingly connected together, an operating head for the piston rod mounted on the inner end of the handle, and a plug connection between the piston and piston rod anchored to the piston and telescoping into the adjacent piston rod section and being non-rotatable relative to said piston rod section.

130 13. In a fountain shaving brush, a tubular internally threaded handle having an open end, a brush head removably mounted in the open end, a piston threaded in the handle, a piston rod for operating the piston formed of telescoping sections rectangular in end view and interlockingly connected together, an operating head for the piston rod mounted on the inner end of the handle, and a plug connection between the piston and piston rod anchored to the piston and telescoping into the adjacent piston rod section and being non-rotatable relative to said piston rod section.

135 14. In a fountain shaving brush, a tubular internally threaded handle having an open end, a brush head removably mounted in the open end, a piston threaded in the handle, a piston rod for operating the piston formed of telescoping sections rectangular in end view and interlockingly connected together, an operating head for the piston rod mounted on the inner end of the handle, and a plug connection between the piston and piston rod anchored to the piston and telescoping into the adjacent piston rod section and being non-rotatable relative to said piston rod section.

140 15. In a fountain shaving brush, a tubular internally threaded handle having an open end, a brush head removably mounted in the open end, a piston threaded in the handle, a piston rod for operating the piston formed of telescoping sections rectangular in end view and interlockingly connected together, an operating head for the piston rod mounted on the inner end of the handle, and a plug connection between the piston and piston rod anchored to the piston and telescoping into the adjacent piston rod section and being non-rotatable relative to said piston rod section.

145 16. In a fountain shaving brush, a tubular internally threaded handle having an open end, a brush head removably mounted in the open end, a piston threaded in the handle, a piston rod for operating the piston formed of telescoping sections rectangular in end view and interlockingly connected together, an operating head for the piston rod mounted on the inner end of the handle, and a plug connection between the piston and piston rod anchored to the piston and telescoping into the adjacent piston rod section and being non-rotatable relative to said piston rod section.
